BOBBIN STRIPPER

Ernest H. Vowles, Fitchburg, Mass., assignor to
 Brown Engine & Machine Company, Fitchburg,
 Mass.

Application January 12, 1942, Serial No. 426,436

7 Claims. (Cl. 28—20)

This invention relates to a machine for stripping waste from bobbins which have been ejected from automatic weft-replenishing looms, after substantial but incomplete exhaustion of weft thereon. A machine for this general purpose is shown in my prior Patent No. 1,473,265 and certain features therein shown are incorporated in the machine disclosed in this application.

It is the general object of my present invention to improve the machine shown in my prior patent in numerous and important respects. Such improvements include the provision of improved conveying means to feed bobbins to the machine and to advance them continuously to the stripping jaws, the provision of improved and simplified pusher slides for forcing the bobbins through the stripper jaws, the provision of an improved construction of stripper jaw, and the provision of improved pneumatic means for removing the stripped yarn or waste from the machine.

My invention further relates to arrangements and combinations of parts which will be herein-after described and more particularly pointed out in the appended claims.

A preferred form of the invention is shown in the drawings, in which

Fig. 1 is a plan view of my improved machine, with an upper frame extension shown in section and with certain parts broken away;

Fig. 2 is a sectional side elevation, taken along the irregular line 2—2 in Fig. 1;

Fig. 3 is an enlarged plan view of the feeding conveyor, partially broken away;

Fig. 4 is a partial side elevation, partly in section and looking in the direction of the arrow 4 in Fig. 3;

Fig. 5 is a transverse sectional view, taken along the line 5—5 in Fig. 4;

Fig. 6 is a partial side elevation, partly in section and showing certain features of the conveyor drive;

Fig. 7 is a partial side elevation of one of the simplified pusher slides;

Fig. 8 is a partial front view of the slide and pusher, looking in the direction of the arrow 8 in Fig. 7;

Fig. 9 is a partial sectional plan view, taken along the line 9—9 in Fig. 8;

Fig. 10 is a side elevation, partly in section and showing the function of the stripper jaws;

Fig. 11 is a partial plan view of a pair of stripper jaws, looking in the direction of the arrow 11 in Fig. 10;

Fig. 12 is an enlarged side elevation of one of

the jaws, looking in the direction of the arrow 12 in Fig. 11;

Fig. 13 is a diagrammatic plan view, showing successive operative positions of the stripper jaws with respect to the bobbin-conveying means; and

Fig. 14 is an enlarged plan view of a portion of the bobbin conveyor chain and attached parts.

Referring to Figs. 1 and 2, my improved bobbin stripper comprises a frame F providing a horizontal bearing 20 for the main driving shaft 21 and also providing a support 22 for the lower end of a fixed upright shaft 23. The upper end of the shaft 23 is supported in fixed position in an upper frame extension or bracket F'.

A cam cylinder 25 is mounted on the shaft 23 and is fixed to the shaft, so that it is held from all movement, either vertical or angular. The cam cylinder 25 is provided with cam grooves 26 and 27 in its cylindrical surface and also with cam grooves 28 and 29 in its lower end surface, the use of which cam grooves will be hereinafter described.

The devices by which the waste is stripped from the bobbins in my improved machine are mounted on a frame-work or head H (Figs. 1 and 2), centered on the shaft 23 but freely rotatable relative thereto. A ring gear 30 (Fig. 2) is mounted on the lower end of the head H and is engaged by a pinion 31 which is connected through a short shaft 32 and bevel gear 33 to a bevel gear 34 on the inner end of the main driving shaft 21, which shaft may be continuously rotated by a belt 35 on a pulley 36 or in any other convenient manner. The weight of the head H and attached parts is carried by a thrust bearing 38 which rests on the upper face of the support 22 in which the lower end of the fixed shaft 23 is secured.

The head H is provided with a plurality of upright guideways 40 (Fig. 1) in which slides 41 are vertically slidable. Each slide is provided with a cam roll 42 (Fig. 2) which is received in the groove 27 in the fixed cam cylinder 25, thus reciprocating each slide 41 as the head is rotated.

Each slide 41 has a pusher 44 (Figs. 7 to 9) formed at the lower end of the slide and adapted to engage the upper end of a bobbin and to push the bobbin downward through the stripping jaws during the first part of the bobbin stripping operation.

It will be noted that the pushers 44 are always in alignment with the stripping jaws and that it is unnecessary to remove the pushers from

such alignment to permit feeding of bobbins downward, as was required in my earlier machine. Many parts are thus omitted in my improved construction.

In place of the rather unsatisfactory hopper feed shown in my earlier patent, I have provided a feeding conveyor by which the bobbins are maintained in upright position and are progressively advanced horizontally to the stripping mechanism.

My improved conveyor comprises a conveyor chain 50 (Fig. 14) to which are attached a series of sheet metal bobbin receivers 51 and a series of spacing blocks 52, preferably of wood. The conveyor chain 50 is mounted on sprockets 54 (Fig. 6) and 55 (Fig. 4), which sprockets are carried on shafts 56 and 57, rotatably supported at opposite ends of the conveyor frame 60 (Figs. 4 and 5). The shaft 56 is extended downward, as indicated in Fig. 6, through a fixed bearing 62 and is provided with a sprocket 63 at its lower end, connected by a chain 64 to a driving sprocket 65 (Fig. 2). The sprocket 65 is mounted at the lower end of a short shaft 66, rotatable in a fixed bearing 67 and having a pinion 68 at its upper end which is in continuous engagement with the ring gear 30. Through these connections, the conveyor chain and the parts mounted thereon are continuously advanced in the direction of the arrow *a* (Fig. 3) as the stripping head is continuously rotated. The bobbin-receiving members 51 on the chain are so spaced that a bobbin is advanced to stripping position each time one of the slides 41 and its associated parts is advanced to coacting position.

Any lost-motion or slackness in the conveyor chain 50 may be taken up by an adjusting screw 69 (Fig. 3) which is mounted in a movable sliding member 70 and abuts a lug 71 in the frame 60. The sliding member 70 provides upper and lower bearings for the shaft 57 on which the outer sprocket 55 is mounted.

The open outer ends of the bobbin-receiving members 51 are normally closed by side plates 72 and 73 and by a curved end plate 74 (Fig. 3). At the inner end of the conveyor adjacent the stripping mechanism, a fixed top guide plate 77 (Fig. 1) and a yieldable top guide plate 78 (Fig. 3) are mounted on the conveyor frame or on parts associated therewith. The guide plates 77 and 78 coact to provide a guide slot 80 along which the advancing bobbin is guided into the path of movement of the stripping devices. The slot 80 thereafter assists in moving the bobbins out of the conveyor members 51 and in radially positioning the bobbins for seizure by the stripper jaws. The free end of the cover plate 78 is sufficiently resilient to yield outwardly or toward the axis of the stripping mechanism as the bobbin is advanced in an anti-clockwise direction as viewed in Fig. 1.

Upright plates 82 (Figs. 1 and 2) are mounted on the guideways 40 at the rear or following side of each pusher 44 and assist in holding the bobbins upright as they are removed from the conveyor members 51 and before they are operatively engaged by the pushers 44.

Upper and lower stripping jaws 90 and 91 (Fig. 10) are provided at the lower end of each guideway 40, a pair of jaws 90 and a pair of jaws 91 being provided for each stripping unit and the jaws of each pair having meshing segmental teeth, as indicated at 92 in Fig. 11.

Suitable actuating mechanism is provided for opening the jaws 90 and 91 as indicated in Fig. 13 as they approach position for receiving a bobbin 75

from the feeding conveyor, and for closing the jaws on the bobbin as the jaws and bobbin are moved onward for the stripping operation. The mechanism for thus opening and closing the jaws 90 and 91 is disclosed only in part herein, as it forms no part of my present invention and may be as shown in detail in Fig. 5 of my prior patent.

For the purpose of this application, it is sufficient to state that the jaws are opened and closed by rolls 94 and 95 (Fig. 2) as said rolls are acted upon by the cam grooves 28 and 29 in the lower end of the fixed cam cylinder 25. The springs 96 shown in Fig. 2 permit the jaws to yield slightly when gripping a bobbin, thus permitting slight variations in bobbin diameter without detriment to the stripping operations.

While the general outline and operation of the stripping jaws 90 and 91 is substantially as disclosed in my prior patent, the specific construction of the bobbin-engaging members of the jaws is much improved, both in operation and also in ease and economy of manufacture.

These jaw members 100, as shown in Figs. 11 and 12, each comprise a semicircular plate 101 having a semi-circular hub 102 depending therefrom and provided with segmental screw threads 103 on its inner and bobbin-engaging face. A coacting pair of these jaw members may be conveniently formed by threading a complete circular unit and thereafter cutting the unit apart along one diameter, as indicated at 104 in Fig. 11. Segmental helical ridges are easily formed in this manner and such ridges are found well adapted to loosen and remove waste from a bobbin. The inner faces of the jaw members 100 may be hardened and otherwise treated to increase their wearing qualities.

In the operation of the machine, the bobbins *B*, after being enclosed by the stripping jaws 90 and 91, are pushed downward by the associated pusher 44 on the associated slide 41, thus stripping the waste on the bobbin from near the butt of the bobbin toward the tip thereof. As the bobbin is thus forced downward, the butt of the bobbin is passed between a pair of spring-actuated latches 110 (Fig. 10), mounted on arms 111 secured to the lower ends of upright bars 112 slidably mounted in the guideways 40 and each provided with a roll 114 (Fig. 2) traveling in the lower cam groove 26 in the cylindrical side wall of the cam cylinder 25. The arms 111 are thus moved successively downward to pull the bobbins entirely through the stripping jaws 90 and 91 and to thus complete the stripping operation.

The latches 110 do not grip the bobbins, however, so that as soon as a bobbin is free of the stripping jaws it may drop downward out of the stripping mechanism. This point in the proceedings is reached after each bobbin has made approximately a half revolution from the feeding point and while the bobbin is alongside the enlarged open end of a pneumatic casing 120 having an exhaust fan 121 associated therewith. This exhaust apparatus receives the waste yarn as it is freed from the bobbins and delivers the same through a discharge opening 122 to any suitable receptacle, not shown.

Having described the construction and operation of my improved bobbin stripping machine, it will be seen that the operation is continuous and that the slides and pushers have only a simple vertical reciprocating movement, while the bobbins *B* have a continuous horizontal movement, first in the feeding conveyor and second in the stripping jaws. Continuous and satisfac-

tory operation of the machine is thus made possible.

Having thus described my invention and the advantages thereof, I do not wish to be limited to the details herein disclosed, otherwise than as set forth in the claims, but what I claim is:

1. In a bobbin stripper, a continuously rotated stripping mechanism, a continuously actuated feeding conveyor, and means to transfer a bobbin from said conveyor to said stripping mechanism and to move said bobbin continuously forward during such transfer.

2. In a bobbin stripper, a continuously rotated stripping mechanism, a continuously actuated feeding conveyor, said conveyor and said mechanism being operated in a fixed speed relation, and means to transfer a bobbin from said conveyor to said mechanism and to continue the forward movement of said bobbin in the same general direction during such transfer.

3. In a bobbin stripper, a continuously rotated stripping mechanism, a continuously actuated feeding conveyor, and means to transfer a bobbin from said conveyor to said stripping mechanism, said bobbin being given a single continuous forward movement and at uniform speed by said conveyor, said transfer means and said stripping mechanism.

4. In a bobbin stripper, means to feed a bobbin horizontally to stripping position, means to move said bobbin in a circular path about a fixed vertical axis during the stripping operation, and additional means to move the bobbin downward as it is advanced in its circular path, thereby stripping the waste therefrom.

5. In a bobbin stripper, a pair of stripping jaws, a slide vertically reciprocated above said

jaws, and a pusher fixed on said slide and reciprocated therewith and having no transverse displacement relative thereto, and said pusher being effective to engage a bobbin gripped between said jaws and to push said bobbin downward, thereby stripping the waste therefrom.

6. In a bobbin stripper having bobbin-stripping mechanism continuously rotated about a fixed vertical axis, that improvement which comprises 10 a conveyor chain mounted for movement in a substantially horizontal plane and in a closed path which is closely adjacent said stripping mechanism at one point, a plurality of bobbin-holding members mounted in spaced relation on said chain and thereby advanced successively to transfer position, means to drive said chain continuously and in fixed speed relation to the continuous rotation of the stripping mechanism, and means on said rotated stripping mechanism effective to successively remove bobbins from the bobbin-holding members on the conveyor chain and to operatively position said bobbins in said stripping mechanism.

7. In a bobbin stripper, in combination, bobbin-stripping mechanism, means to advance the bobbins and stripping mechanism in a circular path about a vertical axis during the stripping operation, and pneumatic means effective to remove from the stripping mechanism the yarn stripped from the bobbins, said latter means comprising an exhaust device and a fan-shaped intake therefor having a widened and concave entrance end portion which is horizontally closely adjacent the locus of movement of said stripping mechanism and bobbins.

ERNEST H. VOWLES.
